UNITED STATES PATENT OFFICE.

ATWOOD D. FRITTS, OF HOBOKEN, NEW JERSEY.

DESIGN FOR A DOOR-HINGE.

SPECIFICATION forming part of Design No. 31,442, dated August 22, 1899.

Application filed July 20, 1899. Serial No. 724,563. Term of patent 14 years.

To all whom it may concern:

Be it known that I, ATWOOD D. FRITTS, a citizen of the United States, residing at Hoboken, in the county of Hudson and State of New Jersey, have invented and produced a new and original Design for a Door-Hinge, of which the following is a specification.

In the accompanying drawings, Figure 1 is an elevation of a hinge, showing my new design; and Fig. 2 is a plan view of the same.

The leading or material features of my design consist of the concave or curved portions *a b c d*, the top and bottom straight edges *ef*, and the straight vertical ends *h i*.

As shown in the drawings, the leaf *A* of the hinge is of greater length than the leaf *B* and

is concave or curved on its top and bottom edges at *a b* from the straight edges *ef* to the vertical straight end *h*. The leaf *B* has concave or curved portions *c d* between the top and bottom straight edges *ef* and its straight vertical end *i*. There are screw-holes in both leaves of the hinge. 20

I claim—

The design for a door-hinge substantially 25 as described and shown.

Signed by me this 19th day of July, 1899.

ATWOOD D. FRITTS.
